UNITED STATES PATENT OFFICE.

MARIUS OTTO, OF PARIS, FRANCE, ASSIGNOR, BY MESNE ASSIGNMENTS, TO AMERICAN OZONE COMPANY, OF NIAGARA FALLS, NEW YORK, A CORPORATION OF NEW YORK.

MEDICAL OZONIZER.

SPECIFICATION forming part of Letters Patent No. 790,655, dated May 23, 1905.

Application filed June 6, 1903. Serial No. 160,396.

To all whom it may concern:

Be it known that I, MARIUS OTTO, doctor of science, residing at No. 5 Avenue du Bois de Boulogne, Paris, France, have invented a certain new and useful Medical Ozonizer; and I do hereby declare the following to be a full, clear, and exact description of the invention, such as will enable others skilled in the art to which it appertains to make and use the same.

10 The invention which is the subject of the present application for a patent relates to a process of ozonization for therapeutic purposes.

The medical ozonizer usually consists in principle of a small glass tube containing ozone, which is produced by a Ruhmkorff coil, itself being operated by an ordinary vibrator or by a Wenheft break; but reduced to these elements the ozonizer placed in the hands of patients presents a certain danger, because of the violence of the shocks of the Ruhmkorff coil. To obviate this serious drawback, I have invented a medical ozonizer herein described, and represented in detail on the drawings attached.

Figure 1 is a diagrammatic view of the whole apparatus. Fig. 2 is a side elevation with the side of the case removed. Fig. 3 is an elevation of the apparatus in which the iron box is represented cut in order to show the resonator and the condenser which it contains. (Seen in plan in Fig. 5.) Fig. 4 is a plan of the apparatus. Fig. 5 is a plan of the lower box.

35 In said drawings, ρ indicates a battery or other suitable source of electricity, which is in the circuit of the primary of an induction-coil 11 by means of the wires 17, 18, and 19. The usual condenser π and "make and break" 40 σ are inserted between the wires 17 and 19. The induction-coil 11 is of the "step-up" type, and the secondary coil is connected by the wires 13 and 14 with a pair of condensers 9 and 10. A sparking gap 12 is inserted between the wires 13 and 14 to increase the tension of the current. The condensers 9 and

10 increase the capacity of the circuit, and they are connected at the other side to a pair of resonators 7 and 8 by the wires 17 and 16. These resonators consist of two spirals 50 of wire, Figs. 3 and 5, wound on an insulating-support formed, for example, of wooden spokes 20 and separated by an insulating-plate 21. If now a suitable point 25 26 of each of the windings is connected with a terminal of 55 the circuit having the spark-gap 12, a resonance of waves is obtained which manifests itself in an additional increase in the tension at the ends of the coils. Leading from the ends of the coils are the wires 24 and 23, which convey this current of increased tension through their terminals 5 and 6 to the electrodes 1 and 2 of the ozonizer. Said ozonizer consists in general of a glass tube or chamber in which the said electrodes 1 and 2 are mounted, as 60 shown in Fig. 1. This tube is provided at its lower end with an air-injecting tube 3, by which the air to be ozonized is injected into the chamber, whereupon the oxygen of the air is ozonized by the discharges passing between the electrodes, and passes out through the trumpet-shaped opening 4, where it is inhaled by the patient.

The various elements are suitably arranged in a box $a b c d$, of which the sides $a b$ joined 75 together can be removed, and the accumulators ρ are themselves placed in accessible compartments.

The discharge excites the specially-modeled duplicate resonator formed by two spirals 80 superposed, which is placed with the two auxiliary condensers 9 and 10 in a drawer situated at the lower part of the apparatus. This disposition allows of the easy adjustment of the elements.

Having thus described my invention, the following is what I claim as new therein and desire to secure by Letters Patent:

A medical ozonizer comprising a suitable source of electricity, an induction-coil, a circuit connecting said source of electricity with the primary coil of said induction-coil, a con-

denser and a make-and-break device in said circuit, a resonator, a circuit connecting said resonator with the secondary coil of said induction-coil and provided with condensers and 5 a spark-gap, an ozonizer and a circuit connecting both poles of said ozonizer with said resonator.

In testimony whereof I have hereunto set my hand in the presence of two subscribing witnesses.

MARIUS OTTO.

Witnesses:

OTTO MUNK,
W. M. KUEHNE.
